PRODUCTION OF LUBRICATING OILS FROM
NAPHTHENIC CRUDESEarl M. Honeycutt, West Chester, Pa., assignor to Sun
Oil Company, Philadelphia, Pa., a corporation of New
JerseyFiled Apr. 13, 1960, Ser. No. 21,964
3 Claims. (Cl. 208—97)

This invention relates to the production of lubricating oil from naphthenic crude petroleum, and more particularly to a method involving the vapor phase treatment of the lubricating oils with a liquid alkaline material.

It is known in the art to produce lubricating oils from naphthenic crudes by flashing the oil to produce vapors and contacting the latter with a liquid alkaline material. Following this contact, the hydrocarbon vapors are condensed to obtain a plurality of lubricating oil distillates having different viscosity and boiling range. This method of producing lubricating oils is advantageous since the presence of the alkaline material in the distillation improves the color and color stability of the distillates which are obtained. Also, the alkaline material reacts with naphthenic acids in the vapors to produce salts from which the naphthenic acids can subsequently be recovered. The use of alkaline material in the distillation is further advantageous in that it makes it unnecessary to provide separate treatments with alkaline material for each of the distillate products which are desired.

In order to perform this process for producing lubricating oils, a zone is provided above the flash chamber, through which zone the liquid alkaline material is circulated. The temperature in this zone is typically in the range from 600 to 725° F., and the alkaline material employed is usually molten caustic soda. During the passage of vapors through the zone, some of the hydrocarbon constituents of the vapors are condensed. As a result of this condensation, and of reaction of naphthenic acids with caustic soda, the alkaline material as it leaves the treating zone contains alkali metal naphthenates and liquid hydrocarbons in addition to the caustic soda. The desired concentrations of components of the liquid material in the treating zone is maintained by removing a drag stream externally of the treating zone and adding fresh caustic soda to the circulating stream to replace the material removed. Typically the alkaline material as it is withdrawn from the treating zone contains 60 to 95 weight percent of liquid hydrocarbon, 3 to 30 weight percent of alkali metal naphthenates and 0.2 to 10 weight percent of alkali metal hydroxide. Naphthenic acids and hydrocarbon oil are usually recovered separately from the drag stream, and the hydrocarbon oil recycled to the treating zone to help maintain the desired oil content.

It is important in the operation of this process that the viscosity of the alkaline material be controlled so that the alkaline material can be satisfactorily handled. In order to help maintain the viscosity at a satisfactory low level, the oil content of the alkaline material is regulated. When it is necessary to reduce viscosity, the amount of relatively non-viscous oil in the alkaline material is increased. This can be done for example by condensing more of the hydrocarbon vapors which are passed through the treating zone. This is disadvantageous, however, since it reduces the yield which is obtained of desired lubricating oil distillates. The problem of maintaining satisfactorily low viscosity is particularly acute when the naphthenic acid content of the vapors passed through the treating zone is relatively high. The naphthenate salts build up in such case to the extent that an excessive amount of relatively non-viscous oil must be provided in order to maintain satisfactorily low viscosity.

In order to overcome these problems and disadvantages

2

of prior art operation, the oil feed to the process is subjected according to the invention to a cracking operation before introduction into the treating zone. The cracking is controlled to provide certain changes in the composition and properties of corresponding boiling range fractions of the oil. The refractive index of the oil is increased by the cracking to obtain an increment in refractive index which is within the range from 0.005 to 0.02. The ASTM acid number of the oil is reduced in the cracking to below 1.5 mg. of KOH per gram, and usually to within the range from 0.1 to 1.5 mg. of KOH per gram. Usually the acid number prior to the cracking is at least 2 mg. of KOH per gram; the acid number is usually not greater than 8 mg. of KOH per gram. The acid number of the cracked product is usually in the range from 5 to 75 percent, preferably 10 to 50 percent, of the acid number prior to cracking. Complete removal of naphthenic acids in the cracking is usually not feasible, but may be approached in some cases. The extent of conversion of the charge to the cracking operation to gas, gasoline and coke is usually in the range from 5 to 30 weight percent, e.g. 1 to 5 percent conversion to gas, 3 to 20 percent to gasoline and 1 to 7.5 percent to coke.

The reduced acid number of the hydrocarbons as produced in the cracking contributes to reduction of viscosity in the liquid alkaline material in the subsequent treatment of the cracked vapors. The increased refractive index as a result of the cracking indicates an increased content of aromatic hydrocarbons, resulting in the lubricating oil distillates' having superior properties for various uses, e.g. as rubber processing oils.

The invention will be described more particularly in connection with the attached drawing which is a schematic flow sheet of one embodiment of the invention.

35 Naphthenic crude petroleum is introduced through line 12 into topping zone 10 wherein gas oil and lighter fractions are removed as indicated by line 14. The residue from the topping contains lubricating oil constituents and is introduced, at a temperature for example in the range from 650 to 750° F., through line 16 into flash zone 18. The flash zone is operated under vacuum, usually at a pressure in the range from 40 to 100 mm. of Hg absolute, though other degrees of vacuum can be used, and lubricating oil constituents are vaporized and removed through line 22. The residue from the flash distillation is removed through the line 20.

50 The lubricating oil vapors are introduced into cracking zone 24 wherein they are contacted with a granular solid cracking catalyst at an elevated temperature in the range from 500 to 750° F. Some cracking of hydrocarbon constituents to lower boiling constituents occurs and also some decomposition of naphthenic acids, probably to produce hydrocarbons and carbon dioxide as products. The cracked vapors are introduced through line 26 into distillation and treating tower 30.

55 In the treating zone of tower 30, the vapors are contacted with a liquid alkaline material which is passed downwardly over distillation trays in the treating zone. When the alkaline material reaches the lowest tray in the treating zone, it is removed through line 32. A drag stream is removed through line 34 and subjected to conventional treatment for separate recovery of naphthenic acids and hydrocarbon oil. The alkaline material withdrawn through line 32 contains liquid hydrocarbons, 60 sodium naphthenates and sodium hydroxide. The bulk of the withdrawn material is recirculated to the top of the treating zone through lines 28 and 35, fresh sodium hydroxide being introduced through line 36 to replace that which reacts with naphthenic acids in the treating zone.

70 The treated hydrocarbon vapors pass upwardly into the rectifying section of tower 30, and distillate lubricat-

ing oils which are obtained in the rectifying zone are removed as indicated by the lines 40. The light products produced in the cracking are withdrawn from zone 30 through line 38 for suitable further processing as known in the art. Any liquid material at the bottom of the tower is removed through line 42.

As a typical example of operation according to the invention, Quiriquire crude petroleum is topped to remove lower boiling material, and the residue is vacuum flashed to obtain a distillate having normal boiling range of about 500 to about 1000° F. and having acid number of 6 mg. of KOH per gram. This fraction is subjected to catalytic cracking. The portion of the cracked products which boils above 400° F. has acid number of less than 1.0 mg. of KOH per gram. The products of cracking are passed through a treating zone containing sodium hydroxide, and the treated vapors are rectified to obtain a plurality of lubricating oil distillates. A typical distillate obtained in this manner has normal boiling range of about 808 to 865° F., specific gravity at 60° F. of about 0.980 and refractive index at 20° C. of 1.5576.

By way of comparison, a lubricating oil distillate having boiling range of 815 to 877° F. and obtained in the same way except that the catalytic cracking operation is omitted, has specific gravity at 60° F. of 0.971 and refractive index at 20° C. of 1.5437, as a result of the considerably lower aromatic hydrocarbon content of this distillate as compared with the distillate obtained from the vapors which have been subjected to catalytic cracking. Generally similar relationships between cracked and uncracked distillates are exhibited by lubricating oil distillates having different boiling ranges.

In the operation with the oil which has not been subjected to catalytic cracking, the high naphthenic acid content of the hydrocarbon vapors results in the formation of large amounts of sodium naphthenates in the treating zone, and consequently the viscosity of the liquid material in the treating zone is quite high, unless large amounts of oil are condensed in the treating zone. These difficulties are not encountered in the case of the oil which has been previously cracked, since the naphthenic acid content of the vapors is much less in this embodiment.

The higher aromatic content of the lubricating oil distillates obtained from the oils which have been cracked results in better processability of the oils with rubber compositions, e.g. butadiene-styrene synthetic rubber compositions, and in other properties which make the oil more desirable in rubber compositions where relatively highly aromatic plasticizers or extenders are advantageous.

Cracking catalysts which can be used in the process of the invention include those granular solid cracking catalysts which are known for the conversion of relatively high boiling petroleum hydrocarbons to relatively low boiling hydrocarbons in the gasoline range. Such catalysts include the well-known synthetic silica-alumina, silica-alumina-magnesia, silica-alumina-chromia catalysts, etc., the activated clay catalysts and other known cracking catalysts such as bauxite, lithium carbonate, etc. The synthetic silica-alumina and the activated clay catalysts are preferred for use according to the invention.

The temperature in the cracking operation is in the range from 500 to 750° F., and preferably in the range from 600 to 700° F. These conditions provide the changes in composition and properties of the oil which give the beneficial results according to the invention.

The cracking is preferably performed by passing the oil through a stationary bed of the cracking catalysts. Typical liquid hourly space velocities are those in the

range from 0.5 to 5. Preferably two beds are provided which can be operated alternatively with one bed being regenerated while the other bed is in service for the contact with the hydrocarbon oil. During the regeneration stage, carbon which has been deposited during the cracking stage is burned from the catalysts in a manner which is well known in the art. Although the fixed bed type of cracking is preferred, it is to be understood that the other known types of cracking, such as the moving bed and fluidized catalyst types, can also be employed.

In one embodiment of the invention, lubricating oil vapors are obtained by vacuum flash distillation and contacted with the cracking catalysts, then introduced into the treating zone, vacuum being maintained throughout these operations so that the lubricating oil hydrocarbons remain primarily in the vapor phase.

In another embodiment, the lubricating oil hydrocarbons are contacted in liquid or in mixed phase with the cracking catalyst, and the liquid cracked products are vacuum flashed to obtain vapors which are introduced into the treating zone. In this embodiment, atmospheric pressure or elevated pressure, e.g. up to 15 p.s.i., can be employed if desired. Distillate or residual fractions can be charged to the cracking step.

The cracked products may if desired be subjected to refining operations such as acid and clay treatment prior to introduction into the treating zone for contact with alkali. On the other hand, the lubricating oil distillates recovered from the alkali-treated vapors can be subjected to such treatments if desired. However, such treatments are frequently unnecessary, either before or after the alkali treating.

The invention claimed is:

1. In a process for refining lubricating oils comprising the steps of distilling a naphthenic crude oil to obtain a naphthenic lubricating oil fraction containing naphthenic acids and having an acid number of at least 2 mg. of KOH per gram, countercurrently contacting the lubricating oil fraction in the vapor phase with liquid alkali flowing downwardly in a treating zone to remove naphthenic acids, condensing a portion of the lubricating oil vapors in the alkali treating zone to maintain the viscosity of the liquid alkali at a suitably low level for circulation, and condensing and separating the treated vapors as lubricating oil distillates, the improvement comprising contacting the naphthenic lubricating oil fraction, prior to its introduction to said treating zone, with a granular solid cracking catalyst at a temperature in the range of from 500 to 750° F. to obtain a cracked product having refractive index in the range of from 0.005 to 0.020 greater than that of the original fraction and having an acid number of less than 1.5 mg. of KOH per gram, whereby the quantity of lubricating oil vapors condensed to maintain viscosity is substantially reduced.
2. Process according to claim 1 wherein the lubricating oil fraction is obtained by flash distilling the crude petroleum, and wherein the vaporized fraction is contacted with the cracking catalyst and then introduced into the treating zone.
3. Process according to claim 1 wherein the cracking catalyst is a synthetic silica-alumina cracking catalyst.
